PENDULUM CLOCK HOUSING

Ronald B. Kemnitzer, Lisle, Ill., assignor to
Sunbeam Corporation, Chicago, Ill.

Filed July 9, 1973, Ser. No. 377,464

Term of patent 14 years

Int. Cl. D10—01

U.S. Cl. D10—28

FIG. -1-

FIG. -3-

FIG. -2-

FIG. 4-

FIG. 5-

FIG. 6-

FIG. 7-

FIG. 1 is a right front perspective view of a pendulum clock housing showing my new design;

FIG. 2 is a front elevational view thereof;

FIG. 3 is a left side elevational view thereof;

FIG. 4 is a top plan view thereof;

FIG. 5 is a bottom plan view thereof;

FIG. 6 is a schematic sectional view taken along the line 6-6 of FIG. 2, the internal structural details having been omitted as non-ornamental; and

FIG. 7 is a sectional view taken substantially along the line 7-7 of FIG. 2.

I claim:
The ornamental design for a pendulum clock housing, as shown and described.
